UNITED STATES PATENT OFFICE

ALEXANDER LAZAR, OF PORT ARTHUR, ONTARIO, CANADA

SMOKING-PIPE FILLER

Application filed December 19, 1928. Serial No. 327,158.

This invention relates to certain new and useful improvements in smoking pipe fillers and has for its primary object to provide a tobacco can or pouch having a discharge end 5 or mouth of a size to fit into the bowl of a pipe to facilitate charging the pipe bowl with tobacco.

A further object of the invention is to provide a smoking pipe filler of the above type 10 having a tensioned plunger therein that is capable of being rotated for the purpose of agitating the tobacco in the pouch or can and also for tamping tobacco in the bowl of the smoking pipe.

With the above and other objects in view that will become apparent as the nature of the invention is better understood, the same 15 consists in the novel form, combination and arrangement of parts hereinafter more fully 20 described, shown in the accompanying drawing and claimed.

In the drawing:—

Figure 1 is a top plan view of a smoking pipe filler constructed in accordance with 25 the present invention;

Figure 2 is a side elevational view showing the hinged side door to facilitate filling the pouch or can with tobacco and the chain attached closure cap for the discharge end of 30 the can;

Figure 3 is a bottom plan view of the filler;

Figure 4 is a horizontal sectional view taken on line 4—4 of Figure 2;

Figure 5 is a vertical longitudinal sectional view taken on line 5—5 of Figure 1 showing the tensioned plunger tamper; and

Figure 6 is a cross-sectional view taken on line 6—6 of Figure 5.

Referring more in detail to the accompanying drawing, there is illustrated a smoking pipe filler comprising a pouch or can 1 preferably of oval-formation in cross-section as illustrated for conveniently transporting the 45 same in a pocket, the can 1 having a relatively large side opening door 2 hinged thereto as at 3 and retained in closed position by the catch 4 associated with its free swinging edge. The lower end of the can 1 is provided with a circular discharge opening surrounded by an

annular flange 5 of a size to fit into the bowl of the smoking pipe, the flange 5 retaining the closure cap 6 that is permanently retained upon the can body 1 by the suspension chain 7.

The can 1 is charged through the side door opening and manually operable devices within the can effect agitation of the tobacco therein as well as tamping the tobacco in the pipe bowl. The mounting for such devices and associated parts comprise an opening in the upper end of the can body 1 surrounded by an internal depending annular wall 8 forming a pocket 9 that is closed at its lower end as at 10, while a tubular member 11 depending from the bottom wall 10 of the annular wall 8 and of less diameter than said wall terminates at a point above the lower end of the can and is braced by radial arms 12, the lower end of the tubular member 11 being closed as at 13.

The walls 10 and 13 are centrally provided with openings to accommodate the passage of the plunger rod 14 that extends through the pocket 9 and tubular member 11, the rod 14 being surrounded by the coil spring 15 within the tubular member to be tensioned thereby, the lower end of the spring 15 engaging the bottom wall 13 of the tubular member while the upper end of the spring is engaged by the collar 16 fixed to the rod 14. The rod 14 is depressed by engaging the finger disk 17 upon the upper end thereof that is movable into the pocket 9 as will at once be understood from an inspection of Figure 5. A conical head 18 is carried by the lower end of the rod 14 below the bottom wall 13 of the tubular member 11 and is provided upon its lower peripheral edge with angle fingers 19. Movement of the head 18 through the tobacco in the can and also rotation thereof causes the fingers 19 to agitate the tobacco to facilitate discharge from the can 1 into a pipe bowl.

From the description of the invention, it is believed that the construction and operation thereof will at once be apparent, it being noted that the can 1 is filled through the side door opening while tobacco is retained therein by the closure cap 6 upon the lower end. When it is desired to fill a pipe, the cap 6 is removed and the annular flange 5 at the lower 95 100

end of the can is inserted into the bowl of a pipe. Pressure upon the finger disk 17 causes the rod 14 to be lowered against the tension of the spring 15 while the tamping conical head 18 forces tobacco from the lower end of the can into the pipe bowl and effectively packs the tobacco therein. Also, the rod 14 may be rotated by the disk 17 to cause the fingers 19 carried by the conical head 18 to agitate the tobacco in the can for the purpose of loosening the same and to promote free discharge thereof. The pocket 19 is of a depth sufficient to cause the conical tamping head 18 to be projected outwardly of the discharge opening to enter a short distance into the pipe bowl to accomplish a more perfect packing of the tobacco in the bowl.

While there is herein shown and described the preferred embodiment of the present invention, it is nevertheless to be understood that minor changes may be made therein without departing from the spirit and scope of the invention as claimed.

What I claim as new is:—

- 25 1. In a smoking pipe filler, a container for tobacco having a discharge opening therein, a closure cap for the opening, a tensioned plunger rod in the container alined with the opening, a tobacco agitator and tamper on the lower end of the rod, comprising a conical head, and a plurality of fingers radiating from the peripheral edge of the head.
- 30 2. In a smoking pipe filler, a container for tobacco having a discharge opening therein, a tubular guide in the container alined with the discharge opening, a tensioned plunger extending through the tubular guide, a conical tamping head on the lower end of the rod, tobacco agitating fingers carried by the tamping head, and a finger engaging disk on the upper end of the rod.
- 35 3. In a smoking pipe filler, a container for tobacco having a discharge opening therein, a tubular guide in the container alined with the discharge opening, a tensioned plunger extending through the tubular guide, a conical tamping head on the lower end of the rod, tobacco agitating fingers carried by the tamping head, a finger engaging disk on the upper end of the rod, an annular flange depending from the container and surrounding the discharge opening, and a closure cap fitted on the flange.

In testimony whereof I affix my signature.

ALEXANDER LAZAR.
